DESIGN FOR A GLASS GLOBE

Thomas W. Rolph, Newark, Ohio, assignor to
Holophane Company, Inc., New York, N. Y., a
corporation of Delaware

Application September 11, 1936, Serial No. 64,812

Term of patent 14 years

To all whom it may concern:

Be it known that I, Thomas W. Rolph, a citizen of the United States of America and a resident of Newark, in the county of Licking and State of Ohio, have invented a new, original, and ornamental Design for Glass Globes, of which the following is a specification, reference being had to the accompanying drawing, forming part thereof.

Figure 1 is a side elevational view of the glass globe, showing my new design; and

Figure 2 is a bottom plan view thereof shown on a smaller scale.

I claim:

The ornamental design for a glass globe, as shown.

THOMAS W. ROLPH.
